UNITED STATES PATENT OFFICE.

ARTHUR C. DOLE, SR., AND ARTHUR C. DOLE, JR., OF KANSAS CITY, MISSOURI.

DRAFT REGULATOR FOR STEAM BOILERS.

Application filed March 19, 1921. Serial No. 453,787.

To all whom it may concern:

Be it known that we, ARTHUR C. DOLE, Senior, and ARTHUR C. DOLE, Junior, citizens of the United States, residing at Kansas City, in the county of Jackson and State of Missouri, have invented a certain new and useful Improvement in Draft Regulators for Steam Boilers, of which the following is a specification.

10 Our invention relates to improvements in draft regulators for steam boilers.

It is particularly adapted for use in connection with boilers which supply steam to heating systems, and is adapted for advantageous use in connection with a vapor vacuum heating system.

20 The object of our invention is to provide a novel draft regulating apparatus which is simple in construction, cheap to make, not liable to get out of order, durable, which is efficient in operation, and which may be readily applied to boilers now in use.

25 A further object of our invention is to provide a draft regulating mechanism, which will afford a great economy in fuel, and which is wholly automatic in its operation.

The novel features of our invention are hereinafter fully described and claimed.

30 In the accompanying drawing, which illustrates the preferred embodiment of our invention,

Fig. 1 is an enlarged view of a boiler provided with our improvement shown partly in vertical section and partly in side elevation.

35 Fig. 2 is an enlarged cross section on the line 2—2 of Fig. 1.

Fig. 3 is a vertical sectional view on the line 3—3 of Fig. 2;

40 Fig. 4. is a reduced side elevation of our improved apparatus shown used in connection with a heating system.

Fig. 5 is a plan view, partly broken away, of our improved apparatus.

45 Fig. 6 is an enlarged sectional view on the line 6—6 of Fig. 1.

Similar reference characters designate similar parts in the different views.

50 1 designates an ordinary steam boiler provided with an ordinary hinged draft closure 2 which controls the admission of air to the fire box. 3 designates a hinged draft closure of the usual type for controlling the intake of air to the flue 4.

55 Mounted in the top of the boiler is a pipe 5, on which is mounted a cup-shaped member 6, to which is clamped an ordinary hori-

zontal diaphragm 7, by means of a top plate 8, and bolts 9.

The plate 8 is provided with an upwardly extending arm 10, on which is fulcrumed by a horizontal pin 11 a lever 12.

Rods 13 and 14 are respectively pivoted at their upper ends to the lever 12 at opposite sides of the fulcrum pin 11, and respectively adjacent to the ends of the lever.

65 The lower ends of the rods 13 and 14 are respectively pivoted to the closures 2 and 3.

The arrangement is such that when the lever 12 is swung to the position shown in solid lines in Fig. 1, the closure 2 will be closed and the closure 3 will be opened. The 70 positions of said closures will be reversed when the lever 12 is swung to the position shown in dotted lines in Fig. 1.

To the center of the diaphragm 7 is attached the lower end of a vertical rod 15 which has its upper end pivoted to the lever 12 intermediate of the pivot pin 11 and the rod 14.

Steam pressure in the boiler when the 80 pressure reaches a pre-determined amount will swing the lever 12 to the closed position shown in solid lines in Fig. 1.

When the pressure in the boiler falls to a pre-determined point, the lever 12 will be 85 swung to the open position shown in Fig. 4 and in dotted lines in Fig. 1.

90 For holding the lever 12 in either the open or the closed position, during a substantial change in pressure in the boiler and without having the lever 12 operated to change the positions of the closures 2 and 3, the following described mechanism may be provided.

95 A support for a weight is mounted on the lever 12 and consists of a suitable frame 16 having at its opposite ends respectively two downwardly extending arms 17 which are respectively upwardly and downwardly slidably mounted in two clamping members 18 which are longitudinally slidably mounted on the lever 12, to which said members are adapted to be clamped by set screws 19.

100 The frame 16 is provided with a longitudinal runway 20, on which is adapted to run a rolling weight, preferably comprising a relatively heavy ball 21, which is mounted between lateral guide bars 22, which form part of the frame 16.

105 The arrangement is such that when the lever 12 is oscillated past a horizontal plane, the runway 20 is tilted in opposite directions with respect to the horizontal, so that the

ball weight 21 will alternately travel on the runway 20 across a vertical plane in which is located the fulcrum 11. By means of this construction, when the lever 12 is swung by 5 steam pressure from the position shown in dotted lines to the position shown in solid lines in Fig. 1, the ball weight 21 will roll from a point at the right of the fulcrum pin 11 to a point at the left of said fulcrum pin, 10 as viewed in Fig. 1, in which last named position, the ball weight 21 will hold the lever 12 in the closed position, until the pressure in the boiler falls to such an amount that the atmospheric pressure at the outside of the 15 boiler will force the diaphragm 7 downwardly to the position shown in dotted lines in Fig. 1, upon which the lever 12 and the frame 16 will assume the position shown in dotted lines in Fig. 1, upon which the ball 20 weight 21 will roll on the runway 20, to the position shown in dotted lines in Fig. 1, in which position it will remain until the boiler pressure has risen sufficiently to again swing the lever 12 to the position shown in solid 25 lines in Fig. 1.

For adjustably limiting the movement of the ball weight 21 in opposite directions respectively, there are provided two stop members 23 and 24, which are longitudinally adjustable on the runway 20, to which each stop member may be clamped by means of a set screw 25.

In each of the members 23 and 24, there is provided an inwardly inclined recess, in 35 which is fitted a projecting coil spring 26, against which the ball weight 21 is adapted to strike and which limits the movement in one direction of said weight.

By adjusting the stop members 23 and 24, 40 to different positions, the closures 2 and 3 may be made to open and close at such pressures in the boiler as may be desired.

The springs 26 prevent shock when the ball 21 rolls from one position to the other.

Referring to Fig. 4, which shows the apparatus used in connection with a heating system, 27 designates the steam supply pipe, to which are connected radiators 28, by pipes 29. 30 designates pipes respectively connecting the radiators 28 with a return pipe 31, which is connected in the usual manner to the boiler 1. In the pipe 30 may be provided the usual air eliminator fixture 32.

In the operation of our invention, the 55 frame 16 is adjusted longitudinally on the lever 12 to balance the lever 12 and parts connected therewith, with the ball 21 removed, the stop members 23 and 24 at their farthest distance apart, and the boiler at atmospheric 60 pressure. The ball weight 21 is then mounted on the runway. Vertical adjustment of the frame 16 at its ends is for the purpose of leveling it. The stop members 23 and 24 are adjusted to suit the partial vacuum and 65 steam pressure desired in the boiler 1.

When the pressure rises in the boiler 1 to an amount such that the lever will be swung from the position shown in dotted lines in Fig. 1, to the position shown in solid lines in said figure, steam will fill the radiators 28 70 through the pipes 27 and 29, and the closure 2 will be closed, while the closure 3 will be open. The ball weight 21 will run to the position shown in solid lines in Fig. 1, the runway 20 having been tilted by the lever 12, 75 from the position shown in dotted lines to the position shown in solid lines in Fig. 1.

The radiators 28 will begin to cool as the steam pressure falls in the boiler 1. After the pressure in the boiler reaches atmospheric 80 pressure, the steam in the system will be condensed, thereby creating a partial vacuum in the boiler 1, and pipes connected therewith. The degree of pressure reached by the partial vacuum in the boiler will depend upon 85 the weight of the ball 21 and the position on the runway 20 occupied by the stop member 23. Thus, by adjusting the stop member 23 on the runway 20, the apparatus may be made to operate to open the closure 2 and 90 to close the closure 3 at any desired vacuum in the boiler, independently of the steam pressure required to tilt the lever 12 in the opposite direction. In like manner, by adjusting the stop member 24, the apparatus 95 may be made to open the closure 3 and close the closure 2 at any desired steam pressure, independently of the vacuum pressure which operates the apparatus.

Owing to the fact that there is lost motion and an accelerated rate of speed in the passing of the ball weight 21, from one side of the fulcrum pin 11 to the other side thereof, with respect to the movement of the lever 12, the ball weight 21 will hold the closure 105 2, and also the closure 3 in either the open or the closed position during a substantial change and pressure in the boiler without operation of the lever 12. This construction enables the system to be automatically operated as a vacuum system in which steam 110 will be produced in the boiler at a temperature under 212 degrees, thus affording economy in fuel.

After the pressure in the boiler has formed 115 below atmospheric to an amount in which the external air pressure will depress the diaphragm 7, the lever 12 will be swung from the position shown in solid lines to the position shown in dotted lines in Fig. 1. The ball weight 21 will then roll to the position shown in Fig. 4, and in dotted lines in Fig. 1, thereby holding the lever 12 in a position such that the closure 2 will remain open. The draft being increased steam in 120 the boiler will be again produced until such time as the steam pressure is sufficient to again swing the lever 12 to close the closure 2. As above stated, with our improved apparatus, it may be made to operate at any 125 130

desired steam pressure, say from four ounces to three pounds, independently of the degree of vacuum employed. The latter may be, say from atmospheric pressure to five 5 inch vacuum pressure.

We do not limit our invention to the structure shown and described, as many modifications, within the scope of the appended 10 claims, may be made without departing from the spirit of our invention.

What we claim is:—

1. In an apparatus of the kind described, a lever, means actuated by pressure for oscillating said lever, a support mounted on 15 said lever and having a run way arranged to be tilted in opposite directions when the lever is oscillated, two stop members adjustable toward and from each other on said support and disposed respectively at opposite 20 sides of the fulcrum of said lever, and a weight movable by gravity on said runway when the latter is tilted and arranged to have its movement in opposite directions respectively limited by said stop members, 25 substantially as set forth.

2. In an apparatus of the kind described, a lever, pressure actuated means for oscillating said lever, a support mounted on said lever and arranged to be tilted in opposite 30 directions when the lever is oscillated, two stop members adjustable toward and from each other on said support at opposite sides respectively of the vertical plane of the fulcrum of said lever, and a rolling weight 35 mounted on said support and arranged to have its movement in opposite directions limited by said stop members respectively, substantially as set forth.

3. In an apparatus of the kind described, a lever, pressure actuated means for oscillating said lever, a support longitudinally adjustable on said lever and adjustable vertically at its respective end each end independently of the other, the support being arranged to be tilted in opposite directions when the lever is oscillated, two stop members adjustable toward and from each other on said support at opposite sides respectively of the fulcrum of the lever, and a 50 weight movable by gravity on said support across the vertical plane of the fulcrum of the lever when the support is tilted and arranged to have its movement in opposite directions limited respectively by said stop members, substantially as set forth.

4. In an apparatus of the kind described, the combination with a boiler having a draft closure, of a lever, means connecting the lever and closure by which the latter is 55 opened and closed when the lever is oscillated, means controlled by pressure in the boiler by which the lever is oscillated, and adjustable means by which the lever may be held from swinging in one direction until a predetermined steam pressure is obtained

in the boiler, and by which the lever is held from swinging in the other direction until a predetermined vacuum pressure is obtained in the boiler and independently of changes in the maximum steam pressure 70 employed, substantially as set forth.

5. In an apparatus of the kind described, the combination with a boiler having a draft closure, of adjustable means controlled by pressure in the boiler for moving the closure 75 to the open and closed positions, and arranged to be adjusted so as to move the closure to one of said positions at different steam pressures, and to move the closure to the other of said positions at different vacuum pressures in the boiler and independently of the steam pressure employed, substantially as set forth.

6. In an apparatus of the kind described, a lever, means actuated by pressure for oscillating said lever, a support on said lever, two stop members on said support one adjustable toward and from the other, and a weight movable by gravity on said support when the latter is tilted, and arranged to 80 have its movement in opposite directions limited by said stop members, substantially as set forth.

7. In an apparatus of the kind described, a lever, means actuated by pressure for oscillating said lever, a support on said lever, two stop members each adjustable toward and from the other on said support, and a weight movable by gravity on said support when the latter is tilted, and arranged 100 to have its range of movement limited by said stop members, substantially as set forth.

8. In an apparatus of the kind described, a lever, means actuated by pressure for oscillating said lever, a support vertically adjustable at one end on said lever, two stop members adjustable one toward the other on said support, and a weight movable by gravity on said support when the latter is tilted and arranged to have its range of movement limited by said stop members, substantially as set forth.

9. In an apparatus of the kind described, the combination with a boiler having heating controlling means, of adjustable means controlled by pressure in the boiler for actuating said controlling means and arranged to be adjusted to actuate the controlling means to reduce the heating of the boiler at different steam pressures, and adjustable to actuate the controlling means to increase the heating of the boiler at different vacuum pressures in the boiler independently of the steam pressure employed, substantially as set forth.

In testimony whereof we have signed our names to this specification.

ARTHUR C. DOLE, SENIOR.
ARTHUR C. DOLE, JUNIOR.
